AUTOMOBILE THREE WAY REAR AND SIDE VIEW MIRROR

Raymond B. Kesler, % Irving Seidman, 655 Madison
Ave., New York, N.Y. 10021

Filed July 7, 1969, Ser. No. 18,094

Term of patent 14 years

Int. Cl. D12—14

U.S. Cl. D14—6

FIG. 1.

FIG. 2.

FIG. 3.

FIG. 4.

FIG. 5.

FIG. 6.

FIG. 1 is a front elevational view of an automobile three way rear and side view mirror;

FIG. 2 is a rear view thereof;

FIG. 3 is a top view thereof;

FIG. 4 is a side view thereof;

FIG. 5 is an end view of one edge, the opposite edge being identical; and

FIG. 6 is a perspective view thereof.

I claim:

The ornamental design for an automobile three way rear and side view mirror, substantially as shown.
